S. UNDERWOOD.
CONVEYING BOATS OVER DAMS, &c.

Patented Mar. 19, 1836.

Stephen Underwood of Bath in the County of Grafton State of New Hampshire.

Letters Patent

The Schedule referred to in these Letters Patent and making part of the same, containing a description in the words of the said Stephen Underwood himself, of his improvement "In the Machine for conveying Rafts, Logs, &c. over Dams, shoals, and other obstructions in rivers."

To all whom it may concern, Be it known, that Stephen Underwood of Bath in the County of Grafton State of New Hampshire, has invented an improvement in the means of an apparatus for the conveying of Rafts and Boats and so forth over Dams, shoals, holes or shelves in rivers, and do hereby declare that the following is a full and exact description thereof: I construct two inclined planes, rail ways, which are to be made and fixed, in the manner of the well known marine railways, for hauling rafts out of water for instance I also construct a car, carriage, or cradle, which is to run upon tracks, wheels or rollers in a manner also similar to those used for running reefs to be drawn upon marine railways. One of the before named railways is to be constructed and fixed above the dam or other obstruction its lower end being upstream, and so far below the surface of the water as may be required to float the raft or other load, on to the car or carriage which is then to stand thereon. The other railway is to be below the dam and so forth inclining downstream and in all other respects constructed like that first named. The length of these railways must vary as to adapt them to the situation, how much they are to be placed, and this will be governed by the depth of the water, the height of the obstruction, and the inclination which must be given to cause the power applied to be sufficient to move the load. Should there be no ascending traffic, the inclination of the lower may exceed that of the upper railway.

The upper ends of these railways are to be on the same horizontal

line or nearly so, but they are not to meet together by the whole distance occupied by the length of the car, or carriage, which is to sustain the load, say thirty feet, more or less, according to circumstances. This distance is to be occupied by what I denominate a vibrating railway, whence, far as the rails are concerned, has its upper surface untraversed like that of the inclined plane, so that the gun, or carriage, may run thereon. The timber of which it is composed will be strongly framed together and so stout that they will sustain the car and its load without sensible yielding when it has no support but that of this staff, or guides, upon which it is itself sustained at its centre. The vibrating railway is elevated above the level of the upper ends of the inclined planes, and runs upon guides formed by the ramifications of a staff, which rises at the centre. The boxes, or beams, for these guides will of course be firmly fixed, as they also are to bear the whole weight of the car and its load. The vibrating rail, may it be adjusted, that it will tilt towards either of the inclined planes, will adapt its rail to, and form a junction with them, at their own inclination. I do not think it necessary to describe any particular mode of drawing the car with its load up the inclined plane, as this will be done by manual, animal, water or other power, according to circumstances, and as any good mechanist will be able to devise this part of the structure. It is sometimes necessary to cause the leading to lie horizontally upon the car as it ascends and descends the inclined planes, and to adapt the bearing surface of the carriage to the inclination and delivery of the load, I give you some part of the car, which holds over the bearing timbers of the load, these rest and bear upon guides of wood, the guides being according to the load, when the latter is turned by means of a handspike or otherwise, the load will be suspended by them in any required position. I intend also to make cars for carrying boats, the bodies of which shall be water-tight boxes, into and out of which the boats may be floated. I bearing thus fully described my said invention and the manner in which the same is to be used, and do hereby declare that it consists exclusively in that part of the apparatus employed, which I have delineated, the vibration

ting railway which is intended to move the load at the summit of the inclined plane, and to be adapted, by its vibration, to the plane of either, for the purpose, and in the manner, by one end forth; and I do further declare that I do not intend to confine myself to any particular mode of constructing the said vibrating railway and its appendages, but to vary the same as I may think proper, whilst I attain the desired object, and fitting such a railway to the ascending and descending planes.
